SAMSON D. WRIGHT, OF CLEVELAND HEIGHTS, OHIO

SAFETY MEANS FOR MATERIAL-TRANSFER DEVICES

Application filed February 6, 1928. Serial No. 252,408.

My invention relates to material conveying means generally and more particularly to co-operating transfer devices for such conveying means and still more particularly to safety means between such transfer devices.

One object of my invention is to provide a simple, inexpensive, efficient, and effective means to prevent discharge of material from a material transfer element when no receiving element is in a position to receive the material. Another object is to provide a simple, inexpensive, efficient and effective means to permit transfer of material only when a dischargeable and a receiving element are in co-operative proximity to each other. Another object is to provide a means, automatically operated by movement of transfer elements, to permit the discharge preventing and transfer permitting of material mentioned. Another object is to provide a simple, inexpensive and effective emergency means, manually operable, to permit the discharge preventing and transfer permitting means to be operated when a discharge element and a receiving element are either in or out of co-operative proximity to each other. Other objects will appear, or become apparent or obvious, or will suggest themselves, upon an inspection of the accompanying drawing and in the description of the device shown in this drawing.

In material conveying means it is necessary, quite frequently, that material is transferred from one container or carrying or conveying device or element to another container or device or element during the conveyance or passage of the material from one place to another. This transferring is usually performed by mechanical means or mechanism of some kind which opens and closes a discharge means such as dumping or opening and closing a gate or door. When this mechanism is operated while the discharge means and the material receiving element are in co-operative proximity or relation to each other, the material will be transferred properly from one element to another but when this mechanism is operated while the elements are out of co-operative proximity or relation to each other, the material will not

be discharged into the receiving element and is either lost or must be gathered again with consequent expense. My invention aims to eliminate the possibility of unseasonable transfer of material and to promote transfer of material only when a dischargeable element and a receiving element are in co-operative proximity or relation to each other.

Quite frequently an operator forgets to close the discharge means while the elements are in co-operative positions and moves the elements out of co-operative proximity with the discharge means still open. Since this discharge means is normally prevented from being operated except when two elements are in co-operative proximity, the elements would have to be moved back into co-operative proximity in order to close the discharge means. My invention includes an emergency means to permit this discharge means to be operated to take care of the human possibility of forgetting to close the discharge means at the proper time.

I am aware that my invention can be carried out in different manners. However, in order to illustrate the same, without intention of limiting the same, I have selected one embodiment thereof and have shown the same in the accompanying drawing in which:—

Fig. 1 is a diagrammatical view showing a skip car and a charging car with a hinged door and operating means for the door and a safety means between the cars, embodying my invention; the main valve being in section to show interior parts more clearly.

Fig. 2 is a plan view taken at 2 in Fig. 1 and shows the electric switch as being open and approaching the inclined member of the safety means which is shown in full lines as being moved into switch closing position and in dotted lines as being in normal inoperative position.

Similar reference characters refer to similar parts throughout the views.

In this embodiment of my invention I illustrate an electrically operated transfer car movable horizontally to and from a station and a skip car movable on an incline to and from the same station and a pneumatically operated and electrically controlled means be-

tween the two cars to normally prevent discharge from the transfer car and to permit this discharge only when the cars are in co-operative proximity or relation to each other and to start the means between the cars into discharge operation by means of the movement of the skip car when the same arrives at the station and to stop or arrest this discharge operation by means of the movement of the skip car when the same leaves the station.

Referring now particularly to the apparatus shown in the drawing:—

The scaffold A has the track or rail 10, inclined in the present instance, and the abutment 11 at the lower end of the track to form a definite abutment or station for the skip car B for purposes appearing presently. The upper end of the scaffold and the upper end 20 of the track and the dumping and operating means for the skip car are not shown in the drawing since they bear no definite relation to the safety means and structure at the bottom of the track.

25 The container element B, a wheeled skip car running on and positionally locatable on and guided on the track 10 in the present instance, has the hopper 12 and the bumper 13 to make contact with the abutment 11 and thereby provide a definite rest station for the car B at the bottom of the track and is moved on the track by means of the cable 14 which can be operated by any suitable means not shown in the drawing.

30 The container element C, a wheeled larry car with one hopper and guided on and running on and positionally locatable on the horizontal track 15 in the present instance, has the hinged door 16, the connector bar 17 having one end thereof hinged onto the door and the other end thereof hinged onto the crank 18 on the shaft 19 which is rotated by the pinion 20 in mesh with the reciprocable rack 21 which is operated by the piston 22 operating in the cylinder 23.

35 It is observed that the center of the pin which connects the bar 17 to the crank is below a line drawn through the center of the shaft 19 and the center of the pin which connects the bar 17 to the door. This structure forms a lock means for the gate incorporated in the gate operating means to normally hold the gate firmly in closed position and the lock means can be released and the gate can be opened and closed and again held in closing position upon operation of the gate operating means.

40 The four way operating air valve 24, operated by the handle 25, is mounted on the car C in convenient location for an operator. The pipe 26 connects one of the openings in the valve with one end of the bore in the cylinder 23. The pipe 27 connects another one of the openings in the valve with the other end of the bore in the cylinder. The

5 exhaust pipe 28 extends from another one of the openings in the valve. The pipe 29 connects another one of the openings in the valve 24 with an opening in the control valve D to be described later. The pipe 30 connects another opening in the valve D with the air pressure tank E which may be supplied with pressure air from any convenient or suitable source not shown in the drawing.

60 The electric switch F, of a commercial or special type, in the present instance, has contact elements therein and connected to the leads 40 and 41 respectively and also has a rotatable member carrying a connecting member to connect and to disconnect the contact elements as the same is rotated to open and to close the electric circuit. This rotatable member carries a bell crank lever having the arms or movable contact members 31 and 32; one end of the tension spring 33 is connected onto the arm 31 and the other end thereof is connected onto the car C; the arm 31 and the contact elements and the connecting member being arranged and located so that the spring 33 normally holds the electric circuit open through the switch.

65 The control element, the control valve D mentioned above, in the present instance, comprises a casing divided into three compartments by means of two partitions. The pipe 29 is in communication with the lower compartment and the pipe 30 is in communication with the middle compartment. The valve 34 is seated on the lower one of the partitions and is normally held upon this seat by the spring 35 telescoping over the magnetizable stem 36 of the valve 34 and thereby normally closes communication between the lower one and the middle one of the compartments. The stem 36 extends through the upper one of the partitions, which partition also forms an abutment for one end of the spring 35. The stem extends not quite to the top wall of the casing when the valve is seated to form a space also constituting an air gap so that the valve 34 can be raised off of its seat.

70 The solenoid 37 is telescoped over the outer end of the stem and has the lead 38 thereof connected to the electric feed line 39 and the lead 40 thereof connected to one of the contact elements in the switch F. The line 41 connects the other contact element in the switch to the feed line 42. The feed lines 39 and 42 may be energized by any suitable electric means not shown in the drawing and the car C can be electrically operated by the same source of power in the present instance. When the solenoid is energized, the stem 36 is magnetized and is thereby drawn toward and against the top wall of the casing to complete the magnetic circuit and thereby 75 closes the air gap and raises the valve 34 off of the seat thereof and retains the same in that position as long as the solenoid is in circuit.

An individual external control element, located in a definite relation to the path of both of the containers, is shown as comprising the hinge bracket 43 secured to the rail 15 in the present instance and the lever G pivoted thereon by means of the pin 44 and the upper end of the lever G normally held toward the wheels of the car C, or toward the rail 15, by means of the spring 45 as shown. In Fig. 1 of the drawing, the lever G and the switch F are shown in full lines as being moved into switch closing position and in dotted lines as being in switch opening position.

The upper end of the lever G carries the transversely extending flange 46 having the ends thereof inclined oppositely to each other as seen in Fig. 2. The rod 47 has one end thereof hinged to the arm 31, is guided in the bracket 48 on the car C, and has the handle 49 shown in full lines when the switch F is closed and in dotted lines when the switch is open. The compression spring 50 is interposed between the bracket 48 and the collar 51 on the rod 47.

The lead 52 connects the lead 40 to the lead 41 and has the normally open switch 53 inserted therein so that an electric circuit can be established for the solenoid 37 when the switch 53 is closed to permit the operation of the door 16 through the valve 24 in emergencies or when the switch F is out of commission.

When the car B comes down the incline and just before its reaches the station by contact of the bumper 13 on the abutment 11, the dog 54 on the car B contacts the roller 55 on the lower end of the lever G and moves this lower end toward the track 15 against the tension of the spring 45 as the car B completes its travel to its final station position and, consequently, moves the upper end of the lever away from the track.

When the car C is at the station before the car B arrives there and the spring 50 holds the switch F closed as shown in dotted lines in Fig. 1, the arrival of the car B at the station and the consequent movement of the lever G as described causes the middle portion of the flange 46 to engage the roller 56 on the arm 32 and to rotate the same to the position shown in full lines in Fig. 1 and thereby rotate the rotatable member of the switch F and thereby close the same and complete the electric circuit which includes the solenoid and thereby energizes the same and magnetizes the stem 36 which will then be attracted to the upper wall of the casing of the element D and thereby opens the valve 34 and permits pressure air from the tank E to flow into the pipe 29 and into the operating valve 24 which controls the movement of the door through the cylinder 23 and the connecting mechanism as the operating valve is manipulated.

When the car B is moved upwardly on the

inclined rails and away from the station thereof, the dog 54 moves with the car and eventually disengages the roller 55 whereupon the spring 45 returns the lever G to its original position (shown in dotted lines in Fig. 1) and the spring 50 returns the arm 32 of the switch F to its original switch opening position (shown in dotted lines in Fig. 1) and thereby de-energizes the solenoid and permits the spring 35 to close the valve 34 and prevents air from the tank E to reach the valve 24 so that the door operating mechanism can not be operated even if the valve 24 is manipulated.

In case of an emergency, when it is desired to operate the door when the car B is out of co-operative proximity to the car C or when the car C is away from the station, the switch F can be closed by pushing the rod 47 downwardly to a position shown in full lines in Fig. 1; or, when the switch F is out of order or for other reasons it is desired not to use the switch F, the switch 53 can be closed. In either case, the solenoid is thereby energized and the valve 34 is opened to permit the door to be either opened or closed through the control valve 24.

When the car B arrives at and leaves the station while the car C is not there, the lever G is operated in the manner described above. Normally, when neither one of the cars is at the station, the spring 45 retains the flange 46 toward the rail 15 as shown in dotted lines in Fig. 2. When the car B arrives at the station, the dog 54 moves the flange 46 into the position shown in full lines in Fig. 2. Now when the car C, with the switch F thereon, moves on the rail 15 in a path indicated by the line 57 and approaches the station from either side, the roller 56 contacts the corresponding inclined end of the flange 46 and, as the car C advances toward the station, rotates the arm 32 from the dotted line position to the full line position shown in Fig. 1 and thereby closes the switch F as the car C arrives at the station when the car B is already there.

When the car B is not at the station when the car C arrives there, the spring 45 holds the flange 46 in the dotted line position shown in Figs. 1 and 2 and the roller 56 clears the flange 46 and the switch F will not be closed by movement of the car C so that the door thereof can not be operated except in emergency cases as described above and can normally be operated only after the car B moves the lever G as described above.

My invention provides a means to normally prevent an operable member on one transfer element from being operated except in emergency cases and also provides a means operated automatically by movement of transfer elements to permit operation of the operable member when two transfer elements

are in co-operative proximity to each other.

A plurality of cars, or equivalents thereof, or other devices, can be associated and corresponding elements or members can be installed on these cars or devices to attain the results described or the equivalents thereof; all equivalent elements or members can be duplicates so that any one of a number of elements can operate in conjunction with any one of a number of co-operating elements.

My invention is applicable to transfer elements other than the one application shown and described and changes can be made in the combination and in the arrangement and in the structure of the elements shown and described; therefore, without limiting myself to the precise application of my invention as shown and described nor to the precise combination nor structure nor arrangement of elements as shown and described,

I claim:

1. In combination, an element movable to and from a station and having a pneumatically operable gate, operating mechanism for said gate, a source of pressure air for said gate, another element movable to and from said station, and a control mechanism for said gate operating mechanism including a valve means normally shutting off said pressure air from said operating mechanism to prevent the operation of said gate and contact means operated by movement of said other element and adapted to contact a member of said valve means to open said valve means to turn on said pressure air for operation of said operating mechanism to operate said gate when said other element arrives at said station and to release said member of said valve means to close said valve means when said other element leaves said station.

2. In combination, an element connected with a source of electricity and movable to and from a station, a pneumatically operable movable gate carried by said element, operating mechanism for said gate, a source of pressure air for said gate operating mechanism, another element movable to and from said station, a valve between said source of air and said operating mechanism, a spring normally closing said valve to prevent said air from operating said gate operating mechanism, a solenoid to open said valve upon energization thereof to permit said air to operate said gate operating mechanism, and contact means between said elements adapted to make electrical connection to energize said solenoid when said other element arrives at said station and thereby open said valve to permit said pressure air to operate said gate operating mechanism only when said other element is at said station and to break said connection to de-energize said solenoid and thereby permit said spring to close said valve and thereby prevent said air from operating said gate operating mecha-

nism after said other element leaves said station.

3. In combination, an element connected with a source of electricity and movable to and from a station, a pneumatically operable gate carried by said element, operating mechanism for said gate including a control valve, a source of pressure air for said operating mechanism, a main valve between said source of air and said control valve, a spring normally closing said main valve to prevent said air from flowing into said control valve and thereby prevent said air from operating said movable member even when said control valve is operated, a solenoid to open said main valve, an electric switch in the electric circuit of said solenoid and normally open to permit said spring to keep said main valve closed, another element movable to and from said station, and contact means between said elements adapted to close said switch and thereby energize said solenoid and open said main valve to permit said air to operate said operating mechanism when said other element arrives at said station and to open said switch again when said other element leaves said station.

4. In combination, an element having a discharge gate, power operating means to open and to close said gate, another element movable toward and away from the first said element, and control means for said operating means including a member on the first said element having movable means adapted to normally shut off power for said operating means, a member on said movable element adapted to move said movable means to turn on power for operation of said gate when said movable element is moved into a discharge receiving relation with said gate, and a manually operable member to control the admission of power to said operating means.

5. In combination, a charging car having a discharge gate, power operating means to open and to close said gate, a skip car movable toward and away from said charging car, and control means for said operating means including a manually operable member to control admission of power to said operating means, a member on said charging car having means to normally shut off power to said control member, and a member on said skip car adapted to turn on power to said control member for operation of said gate when said skip car is moved into discharge receiving relation with said gate.

6. In combination, a charging car connected with a source of electricity and moved to a station, a pneumatically operable gate on said car, a source of pressure air for said gate, a control valve for said gate, a main valve between said control means and said source of air, a spring normally closing said main valve, a solenoid energized by means of said

source of electricity to open said main valve, a normally open electric switch in the electric circuit of said solenoid, a skip car movable to and from said station and having a member to close said switch when said skip car arrives at said station and thereby energize said solenoid and open said main valve to permit said air to operate said gate when said control valve is operated and to release said switch for opening thereof when said skip car leaves said station and thereby de-energize said solenoid and close said main valve to prevent said air from operating said gate.

7. In a material conveying means, a movable receiving element, a dischargeable element, a selectively operable discharge means on said dischargeable element and having a lock means normally keeping the same closed and a power means to operate the same, and a control means operated by movement of said receiving element to put said power means into condition to operate said discharge element when said receiving element is in receiving position in relation to said dischargeable element and to cut out said power means to arrest the operation of said discharge means when said receiving element is out of receiving relation with said dischargeable element.

8. In combination, a material container having a discharge gate thereon, a discharge control means including an operating mechanism for said gate, a power source for said operating mechanism, a control means for said operating mechanism including an automatic power shut off means, a mechanism to open said shut off means including a movable contact member, a receiving container movable into a position to receive material from said material container and having a member adapted to move said contact member to open said shut off means when the receiving container is in natural receiving position, and a selectively operable device to control admission of power to said operating mechanism for selective operation of said gate.

9. In a safety means for material transfer devices, a movable material transfer element, a material transfer element movable angular to the movement of the first said transfer element, an operable gate means between said transfer elements and having a control means including a selectively operable gate operation control device normally ineffective for gate control, a movable contact element moved by a contact member on one of said transfer elements and a movable contact member carried on the other one of said transfer elements and moved by contact with said contact element to render said gate operation control device effective for control of the operation of said gate means.

10. In a safety means for material trans-

fer element movable horizontally, a materially transfer element movable vertically, an operable gate means between said transfer elements and having a control means including a selectively operable gate operation control device normally ineffective for gate control, a movable contact element moved by a contact member on said vertically movable transfer element and a movable contact member carried on said horizontally movable transfer element and moved by contact with said contact element to render said gate operation device effective for control of the operation of said gate means.

11. In a safety means for material transfer devices, two material transfer elements each movable angular to the other, a power operable gate means between said elements, a selectively operable gate operation control device normally cut off from the power source, and members controlled by action of both of said elements to turn on the power for selectively operating said gate means.

In testimony of the foregoing I affix my signature.
